UNITED STATES PATENT OFFICE.

THOMAS F. RAINSFORD, OF CLEVELAND, OHIO.

VALVE-OPERATING MECHANISM.

1,137,532.

Specification of Letters Patent. Patented Apr. 25, 1915.

Application filed October 18, 1912. Serial No. 736,448.

To all whom it may concern:

Be it known that I, THOMAS F. RAINS-
FORD, a citizen of the United States, residing
at Cleveland, in the county of Cuyahoga and
5 State of Ohio, have invented a certain new
and useful Improvement in Valve-Operat-
ing Mechanism, of which the following is
a full, clear, and exact description.

This invention relates to improvements in
10 valve operating mechanism for reciprocating
slide valves of internal combustion en-
gines, wherein a single valve controls both
the admission and exhaust for one cylinder,
the present invention being an improvement
15 over the valve gear or valve operating mech-
anism disclosed in my application, — Serial
No. 687,572, filed April 1st, 1912.

The object of this invention is to provide
a valve gear for a valve of this character,
20 which is simple in construction silent in op-
eration, and gives to the valve the variable
movements necessary for it to function
properly and to produce high efficiency.

My invention may be briefly summarized
25 as consisting in certain novel details of con-
struction and combinations and arrange-
ments of parts which will be described in
the specification and set forth in the append-
ed claims.

30 In the accompanying sheets of drawings,
Figure 1 is a transverse sectional view with
parts in elevation; Fig. 2 is a partial longi-
tudinal sectional view with parts in eleva-
35 tion, the section being taken partly along the
irregular line 2—2 of Fig. 1; Fig. 3 is a de-
tail view of the principal parts of the valve
operating mechanism.

Referring now to the drawings I have
shown a multiple cylinder engine embody-
40 ing my invention which comprises cylinders
10, each containing a piston 11 connected by
the usual connecting rod 12 to a crank shaft
13 inclosed within the crank case 14. At
45 the side of each cylinder is a valve chamber
15, cylindrical in shape and containing a
fixed sleeve or bushing 16 in which is adapt-
ed to reciprocate an endwise movable pis-
ton slide valve 17 which controls both the
50 admission of gases to and the exhaust of
gases from the cylinder with which the valve
is associated.

At about the middle of the sleeve 16 is a

series of ports 18 which are connected to the
upper part of the cylinder by a passageway
19 common to both the ingoing and outgo-
50 ing gases. Above the ports 18 is a series of
ports 20 which communicate with a mani-
fold 21 which is in this case an exhaust
manifold, and below the ports 18 is a series
55 of ports 22 which communicate with a mani-
fold 23, which is in this case an inlet mani-
fold.

The valve has cylindrical bearing portions
at the middle and at its ends which portions
engage the wall of the sleeve 16, and between
each end and the middle, the valve is pro-
60 vided with a reduced portion 17, so that
when the valve is lowered from its mid-posi-
tion, as it appears in Fig. 1, the upper se-
ries of ports 20 and the exhaust manifold 70
21 will be placed in communication with the
passageway 19 extending between the cylin-
der and the middle series of ports 18, and
when the valve is raised from its mid-posi-
65 tion, the lower series of ports 22 and the 75
inlet manifold 23 will be placed in communi-
cation with the passageway 19.

The valve chamber is continued down-
wardly and communicates with the crank
chamber 14, and the valve is hollow so that
70 there can be a direct passage of cooling air
currents through the open top of the valve
chamber through the valve and into the
crank case, this circulation of air through
the valve being caused by the suction of the
75 pistons, inasmuch as the intake side of the
carburetor 24 is connected to the crank case,
as fully described in my prior application
above referred to.

For operating the valve I employ a valve
80 gear which includes a rotating crank shaft
or equivalent eccentric device 25 which is
driven from the main crank shaft 13 at one
half the speed of the main crank shaft,
85 through suitable driving mechanism here
shown as chain and sprocket gearing, design-
ated as a whole by the reference character
26. An arm or lever 27 is pivotally connect-
ed at one end to the crank and at its oppo-
90 site end is pivotally connected to a valve rod 100
28, which at its upper end has a pivotal
connection with the valve. For controlling
the movement of the lower end of the valve
rod, or the connection between the lower end

of this rod and the inner end of the arm 27, I employ a fulcrum device which is movable relative to the arm and in this case consists of a link 29 which is pivotally connected at its upper end to a stationary pin or rod 30, and at its lower end is pivotally connected to the arm 27, at a point between the ends of said arm.

While I do not care to be confined to exact proportions or arrangements of parts, except as I am precisely limited by the terms of the appended claims, I prefer that the link 29 be slightly longer than the throw of the crank 25, and that the link 29 be connected to the arm 27 nearer the end of the arm 27 to which the valve rod is connected than to the end connected to the crank 25. It will be understood that for operating each valve I employ one of these arms 27 and the link 29, but for all the valves I use the same crank shaft 25, the several arms 27 being connected to the cranks of said crank shaft.

It will be seen that the arm 27 is oscillated vertically and is also moved endwise, and that the link 29 controls the path of movement of the axis of connection between the valve rod and the arm 27, and serves as a suspending link for the arm 27, as a movable fulcrum for the arm and as a crank for moving the arm about the axis of the crank 25. In fact, the link and crank, by their combined action, cause the axis of connection between the arm 27 and valve rod to move in such a manner that there is quick opening and closing of the inlet and exhaust ports, and both the inlet and exhaust ports are maintained closed during a major portion of the compression and working strokes. There is, however, a particularly quick downward movement given to said axis of connection and hence to the valve, to cause the opening of the exhaust port, and also the valve is moved very quickly from its lowermost position to its uppermost position to close the exhaust ports and to open the inlet ports.

In Fig. 1 and also in Fig. 3, the valve is shown in its mid-position, and the piston is about to start on its working stroke. During the movement of the valve actuating crank, for about 90° from the position shown in Fig. 1, very little vertical movement will be imparted to the valve, for the reason that both the crank and the link 29 are swinging in the same direction or to the right, as the mechanism is viewed in Fig. 1. Near the close of the working stroke, the valve is given a quick thrust downward to open the exhaust ports, this being due to the fact that the valve operating crank is still moving upwardly, thus rocking the arm 27 about the connection of said arm with the link as the fulcrum, and at the same time, the link 29

rocking the arm 27 about the connection of said arm with the crank as the fulcrum.

At or near the time that the valve actuating crank reaches its uppermost position, the valve is given a long quick upward stroke from its lowermost position to its uppermost position, causing the closure of the exhaust ports and an opening of the inlet ports, this quick upward movement being due to the fact that the crank is now swinging downwardly and the link is swinging upwardly. Thence the valve is moved downward to its mid-position by the combined downward movements of the crank and link, and when the inlet port is closed, the vertical movement of the connection between the arm and valve rod is gradually converted into a substantially horizontal movement, which as before stated, imparts very little vertical movement to the valve and causes the ports to be maintained closed during a major portion of the compression and working strokes. This series of movements are then repeated for the next cycle of engine operation.

Preferably, the three axes or centers of connection of the arm 27 with the crank 25, link 29 and valve rod 28 are on a straight line. The advantages of this arrangement over one wherein the three axes of connection are not on a straight line or on substantially a straight line, are, a more freely swinging construction, the arm is not subjected to locking strains when the arm is tilted into any of its extreme positions; increased leverage between the points of connection of the arm with the link and valve rod. This latter advantage results in faster valve motion at certain points of the cycle of engine operation, and permits the use of greater lap in the valve.

Having thus described my invention, what I claim is:

1. In combination in an internal combustion engine, a cylinder, a slide valve controlling the admission to and exhaust of gases from the cylinder, a valve operating mechanism comprising a rotating member, an arm eccentrically connected thereto, a valve rod connected to the valve and pivotally connected to said arm, and a swinging link pivotally connected to said arm between said rotating member and the valve rod, the axes of connection of said arm with the rotating member, with the link, and with the rod being in a substantially straight line.

2. In combination in an internal combustion engine, a cylinder, a slide valve controlling the admission to and exhaust of gases from the cylinder, a valve operating mechanism comprising a rotating member, an arm eccentrically connected thereto, a valve rod connected to the valve and pivotally connected to said arm and a swinging link pivotally connected to said arm between said rotating

member and the valve rod, the axes of connection of said arm with the rotating member, with the link and with the rod being in a substantially straight line, said link being 5 pivotally connected to a support above the arm and extending from said support downwardly to the arm.

In testimony whereof, I hereunto affix my signature in the presence of two witnesses.

THOMAS F. RAINSFORD
